UNITED STATES PATENT OFFICE.

GIDEON RIETVELD, OF KNOXVILLE, IOWA.

MATCH-BOX.

1,165,908.

Specification of Letters Patent. Patented Dec. 28, 1915.

Application filed April 29, 1914. Serial No. 835,269.

To all whom it may concern:

Be it known that I, GIDEON RIETVELD, a citizen of the United States, residing at Knoxville, in the county of Marion, State 5 of Iowa, have invented certain new and useful Improvements in Match-Boxes; and I do hereby declare the following to be a full, clear, and exact description of the invention, such as will enable others skilled 10 in the art to which it appertains to make and use the same.

This invention relates to match boxes, and has particular application to a pocket match box which is stamped or otherwise formed 15 from a single piece of sheet metal.

In carrying out my invention it is my purpose to provide a match box which is made of a single sheet of metal, so cut and bent that there is but little waste of mate- 20 rial in the process of manufacture.

Still a further object of my invention is the provision of a match box of this character which will embody in its construction the desired features of simplicity, efficiency, 25 durability and strength, and which may be manufactured and marketed at a relatively low cost.

With the above recited objects and others of a similar nature in view, my invention 30 consists in the construction, combination and arrangement of parts set forth in and falling within the scope of the appended claim.

In the accompanying drawings: Figure 35 1 is a perspective view of a complete match safe embodying my invention, the spring cover being shown in its open position. Fig. 2 is a view of the box in side elevation, with the cover in its closed position. Fig. 3 40 is a vertical longitudinal sectional view taken through the box as shown in Fig. 2. Fig. 4 is a transverse sectional view taken through the box. Fig. 5 is a plan view of the blank from which the box is made, the scoring or 45 lines upon which the blank is to be bent being represented by dotted lines. Fig. 6 shows the blank in a partially folded position.

In the manufacture of my box I make use 50 of a single piece of sheet metal which is so bent or folded that a complete box or casing is formed which is open at but one end, and that the top end, and in addition to this

I provide a spring cover which embraces a side wall adapted to overlie what may be 55 called the back face of the box when the spring cover is in closed position, this cover terminating in an angular top plate which is adapted to overlie and constitute a closure for the open top end of the box or casing 60 proper.

Referring now to the accompanying drawings in detail, and particularly to Fig. 5, the letter A designates the blank of sheet metal from which the box is to be formed. 65 This blank is cut as shown in said Fig. 5, that is to say with the substantially rectangular section B which is to be folded to constitute the major portion of the casing or box proper, a relatively long tongue section C which extends from the section B and which tongue section when bent is to form the spring cover, and a pair of relatively small lips D which project from the section B at opposite sides of the tongue C, these 70 lips or flaps D—D being adapted to be bent inward as hereinafter described to constitute the bottom of the box or casing proper.

In forming the casing or box portion of the article, the rectangular section B of the 80 blank is first bent or folded on the longitudinal parallel lines 1—1, so that two side sections 2—2 are formed at right angles to the central section 3, which latter forms the front of the box. Each side section 2 is in 85 turn folded or bent inward on the central longitudinal line 4, so that the inward folded portions 5—5 of the blank will form the back of the box with their edges meeting. The blank now appears as shown in Fig. 6. 90 The flaps D—D are now folded inward to form the bottom of the box. The tongue section C is then bent upward on the transverse line 7 and inward on the parallel transverse line 8 to form the end wall 9 which 95 overlies the bottom of the box or casing proper and which bottom is as herein stated made up of the flaps D—D. The tongue section C adjacent its free end is further folded or bent at right angles on the transverse line 10 so that the cover 11 is formed which constitutes a closure for the open top end 12 of the box or casing. This top cover 11 is further provided with a lug 13 which, when the cover is in its closed position is 105 adapted to snap over and engage with the

top edge of the wall 3 to lock the cover in closed position and thereby retain and preserve the contents of the box.

From the above description, taken in connection with the accompanying drawings, the construction and manner of making my improved one-piece spring cover match box will be readily apparent to those skilled in the art. It will be noted that owing to the natural resiliency or springiness of the material from which the box is made and from the manner in which the cover section C is formed, it is only necessary for the operator, should he desire to open the box, to push up 10 on the top section 11, when the lug 13 will be released from the top edge of the front of the box and the entire cover section C will spring backward away from the box or casing. Likewise, when it is desired to close 15 the box, it is only necessary for the operator to press the cover toward the casing and thus snap the locking lug over the top edge of the front and thus securely close such cover.

It will be noted that I have provided an exceedingly simple, compact and efficient form of match safe, which may be made from a single piece of metal, and that the blank from which the box is formed is to be 20 so cut that there is comparatively little waste. The consequence is that the box may 25

be manufactured very cheaply and consequently marketed at a very low cost.

What I claim is:

As an article of manufacture, a one-piece sheet metal box including a box-like body portion having the front and back and side walls thereof formed by folding a substantially rectangular piece of metal, the opposite side edges of the rectangular piece of metal meeting at the center of the box, said body portion having a pair of spaced in-turned flaps constituting the bottom thereof, the free ends of said flaps meeting at substantially the central longitudinal line of 45 the body portion, and a cover section for the box comprising a spring tongue having a laterally extending bottom section formed integral with the front of the box-like body portion and bowed to overlie the bottom of 50 such body portion, said tongue also having a longitudinally extending section adapted to overlie the back of the box-like body portion, and a laterally extending section at the free end of the tongue adapted to form a 55 cover for the box-like body portion.

In testimony whereof, I affix my signature, in the presence of two witnesses.

GIDEON RIETVELD.
